UNITED STATES PATENT OFFICE

2,609,157

WINDING APPARATUS

Jes Asmussen, Appleton, and Frank Gruper, Menasha, Wis., assignors to Marathon Corporation, Rothschild, Wis., a corporation of Wisconsin

Application November 12, 1947, Serial No. 785,424

3 Claims. (Cl. 242—66)

1

The invention relates to apparatus for winding a continuous web of sheet material into a roll.

It is the customary practice to wind sheet materials, such as a paper web, onto a winder shaft or core by means of a pair of driven rotating drums in frictional engagement with the web being wound onto the winder shaft at the nip of the drums and the wound roll. It is evident that as the amount of paper wound on the winder shaft increases, the diameter of the wound roll increases, resulting in an increased weight or pressure upon the supporting driven rotating drums, with the consequent increase in pressure upon the web being wound. The effect of the increased pressure upon the web is to increase the tension on the web with frequent rupture occurring. Another undesirable result is that the web is wrinkled as it is being wound. Furthermore, the density of the wound roll progressively increases from the winder shaft outwardly towards the periphery.

In order to overcome these difficulties the present invention provides automatic means for controlling the pressure and tension upon the web by compensating for the normal increase in pressure and tension upon the web as it is being wound onto the winder shaft. In this manner a suitable amount of constant tension may be applied to the web at all times.

The problems previously outlined are further complicated when it is desired to use the same winding apparatus to wind webs of different widths or density. For example, if after winding a web of a given width or density into a roll it is desired to use the same winder for a web of different width or density there will be a corresponding change in weight and likewise pressure of the wound roll upon the drum winders for the same linear length of the web. The present invention permits a simple adjustment for webs of different width or density so that the pressure and tension upon the web is always constant and of the same desired amount.

The primary object of the invention is to provide automatic means for controlling the pressure and tension upon a web as it is being wound and to compensate for the increase in weight of a roll of web material as it is being wound with a drum winder.

Another object of the invention is to provide means for the adjustment of the weight or pressure compensating means to allow for change in weight or pressure upon the drums due to operation upon webs of different width or density.

Other objects and advantages will more fully

2

appear from the description and drawings, wherein:

Figures 1 and 1-A represent a front view of a drum winder in combination with means for controlling the pressure of a roll being wound upon the rotating supporting drums;

Figure 2 is a side view of the machine taken along the line 2—2 of Figure 1;

Figure 3 is an elevational view of the compensating cam taken along the line 3—3 of Figure 1;

Figures 4 and 4-A represent a diagrammatic view of the relationship of a hydraulic system with a compensating cam whereby compensating pressure is supplied by the hydraulic system for the changes in weight of the roll as it is being wound;

Figure 5 is a vertical, sectional view of the compensating cam taken along the line 5—5 of Figure 3; and

Figure 6 is a perspective view of the compensating cam.

Referring to the drawings, the apparatus comprises the usual double drum winder mechanism which includes a frame 10, two rotating drums 11 and 12, having their respective shafts 11' and 12' journaled in the frame 10. The drums 11 and 12 are driven in the same direction and at differential speeds. A core assembly 13 having a winder shaft 13' is provided at the nip of the drums 11 and 12 for frictionally winding a web 16 thereon. The winder shaft 13' is journaled in a pair of spaced split bearings 14, which are each secured to a plate 18. The plates 18 are mounted for vertical movement in a pair of spaced guideways 15. The upper and lower portions of each split bearing are pivotally connected by a pin 5. To lock the split bearings 14 about the winder shaft 13', or to permit opening the bearings 14 to allow removal of the winder shaft, a hand operable cam 6 is rotatably mounted on each plate 18 for cooperation with the upper portion of each split bearing. The web 16, such as paper, is suitably threaded between the drums 11 and 12 and attached to the core assembly 13 preparatory to being wound into a roll 17. As the web 16 is wound onto the core assembly 13, the roll 17 increases in diameter and weight whereupon the bearings 14 and their attached plates 18 will slide vertically upwards in the guideways 15.

A pair of cables 19 is provided with one end of each cable to the upper portion of each plate 18 by a connector clamp 70. The other end 19' of each cable 19 is fixedly secured to a sheave 20 as by soldering. A pair of sheaves 20 are keyed

for rotation with a shaft 21 between spaced bearings 90 and 91 mounted on the upper portion of the frame 10 and in which the shaft 21 is journaled. Each sheave 20 is provided with a medially disposed flange 20' thereby forming a pair of spaced grooves 92 and 93. A second pair of cables 7 is provided with one end of each cable secured by a connector clamp 71 to a piston rod 22, and its piston 94, of a pair of spaced hydraulic cylinders 23. The other end of each cable 7 is likewise securely fastened to the sheave 20 as by soldering. As shown in Figures 1 and 1-A, each cable 7 is disposed to be wound in the groove 92 of each sheave 20 and each cable 19 is arranged to be wound in the other groove 93, the two cables being separated by the medial flange 20'. Each cable 7 may have a reach thereof suitably supported by a roller 24 supported in a bracket 24' mounted on the frame 10.

A cam 25 is provided for compensating for the increases in pressure of the roll 17 upon the drums 11 and 12 as it is being wound upon the core assembly 13. The cam 25 is also cut or formed to compensate for or reflect increases in weight when webs of different width or density are wound. The contour of the cam 25 is illustrated in Figures 3, 5 and 6.

As shown in Figure 1, a sleeve 81 is disposed on the shaft 21 and fixed for rotation therewith by pins 82. The cam 25 is keyed to the sleeve 81 for rotation therewith, as well as sliding engagement along the longitudinal axis of the sleeve. The sleeve 81 is of a length to accommodate the cam 25 at its limits of requisite sliding movement as indicated by the phantom outline of the cam. It is understood that the cam 25 may be mounted directly upon the shaft 21. The sleeve 81 is preferred, however, because of the greater ease and simplicity of machining and handling the smaller sleeve element.

Cooperating with the cam 25 is a cam follower 26 such as a steel ball mounted on the end of a bar 27. The other end of the bar 27 is screw threaded in a bracket 28 so that the effective length of the bar 27 may be varied or adjusted by rotating a bar grip 27'. The bracket 28 is pivotally connected to one end of a lever arm 29 by a pin 30. The lever arm 29 is fulcrumed inward of its other end 29' by a pin 31 in a bracket 32 suspended from a support 33. The support 33 is fastened to the top of a horizontally disposed plate 9 which is fastened to frame cross bar 10 by members 8. The end 29' of the lever arm 29 contacts and bears against a pin 34 of an adjustable relief valve 35.

The valve 35 is part of a suitable hydraulic system, diagrammatically illustrated in Figures 4 and 4-A, which may be a Vickers type, manufactured by Vickers, Incorporated, Detroit, Michigan. The hydraulic system comprises the adjustable relief valve 35 connected to a selector valve 39, having a hand lever 39', by a pipe line 104. The selector valve 39 is connected to a balanced piston valve 38 by a pipe line 105. A pressure gage 42 may be inserted in the line 105. The balanced piston valve 38 is connected by a pipe line 106 to an oil reservoir 36 containing a filter 33 and a baffle plate 84. The balanced piston valve 38 is also connected to a pump 37 by a line 102, the pump acting upon the reservoir 36 through a line 103. The balanced piston valve 38 is also connected to a three-way valve 40, having a lever handle 41, by a pipe line 107. Hydraulic piping 108 and 111 connect the ends of the cylinders 23. The three-way valve 40 is

connected to the upper end of cylinders 23 by pipe lines 108 and 111 to enable the fluid to act upon the upper face of each piston 94. The valve 40 is also connected to the other end of each cylinder 23 by pipe lines 109 and 110 to enable the fluid to act upon the lower face of each piston 94. A hand shut-off valve A is located in the line 108. The valve 35 is directly connected to the reservoir 36 by means of pipe line 100. The valves 39 and 40 are connected to the line 100 by pipe lines 101 and 112, respectively. The operation of the hydraulic system will be subsequently described.

In order to reflect and to enable the hydraulic system to compensate for progressive increases in weight of a roll 17 of web material of a given width being wound at any point between the start of the winding operation and the completion thereof, the contour of the cam 25 is designed in the following manner. The pin 34 of the valve 35 has a given maximum travel, for example, one-quarter (1/4) inch. The amount of pin travel is compounded by means of the effective length of lever 29, which may be selected to reflect the amount of pin travel twelve (12) times. For example, with the core shaft assembly 13 weighing 1,000 pounds, and the pressure in the hydraulic system, through the cables 7 and 19, supporting this weight with the desired pressure upon the drums 11 and 12, the pin 34 of valve 35 is set at zero. When the web 16 has been wound on the core assembly 13 to give a fully wound roll 17, the pin has travelled its maximum distance of one-quarter (1/4) inch. The combined weight of core assembly and web material wound thereon is determined and let it be assumed such combined weight is 4,000 pounds. For an intermediate point, say where the combined weight of the core shaft assembly 13 and the web wound thereon is equal to 2,500 pounds, the pin will travel one-eighth (1/8) inch. These amounts compounded twelve (12) times are placed on the cam. This procedure is followed for a suitable number of combined weights intermediate the weight of the core assembly alone and the maximum weight of the core assembly fully wound with a web of material of a given width. In this manner the contour of the cam is determined for a web of given width. For webs of different width, the maximum combined and intermediate weights will, of course, be different. Following the same determinative procedure outlined above, the contour of the cam may be determined for any given web width. The contour of the cam thus determined is illustrated in Figures 3, 5 and 6. Referring to Figures 1 and 1-A, with the cam 25 fixed against horizontal movement, rotation thereof under the cam follower 26 is translated to the pin 34 to react upon the oil in the hydraulic system in a manner to be subsequently described. To compensate for increases in weight for a web of different width, the cam 25 is moved horizontally to another selected position and fixed against horizontal movement thereby presenting another segment of the rotatable cam to its cam follower 26.

Mechanism is provided to slide the cam 25 longitudinally along the sleeve 81 to present a selected area of the cam to the cam follower 26. The cam is provided with end plates 85 and 86 suitably secured thereto by screws 87 and 88 threaded within the threaded openings 87' and 88', respectively. A collar 44, which encircles the sleeve 81, is secured to the end plate 85 and

hence the cam 25. A yoke 45 is fixedly fastened to the collar 44. The yoke 45 is secured to a threaded slideable bar 46 mounted on a rack, supported in brackets 80, comprising spaced rods 47 supported by fixed cross bars 47'. A screw threaded rod 48 is journaled in the bars 47' and passes through the threaded, slideable bar 46. The rod 48 is rotated by means of a rotatable hand wheel or lever 49 through the arrangement of a sprocket 50 secured to an end of the threaded rod 48, a sprocket 50' secured to an end of a hand lever shaft 49', journaled on the frame 10, and a chain 51. The rotation of the threaded rod 48, through the threaded bar 46, will cause the cam 25 to slide longitudinally along the shaft 21 through the yoke 45 and the attached collar 44. To indicate the desired position of the cam 25 on the shaft 21, one end of a cable 52 is secured to the yoke 45 by clamping elements 52'. The other end of the cable 52 is fastened to a weighted member 53, slideable in guideways 53', having its surface marked to form a scale which in combination with a datum line or pointer 54 will indicate the horizontal position of the cam 25 on the sleeve 81. The lower portion of cable 52 is made to assume a vertical position by the suitable positioning of a roller 75. The scale is calibrated to indicate different widths of web. The portion of the cam 25 presented to the cam follower 26 has a direct relationship to the width of web 16 for which compensation must be made as it is being wound in order to maintain the tension upon the web, or the pressure between the drums 11 and 12 and the roll being wound, at a desired constant amount.

The apparatus described operates as follows. The position of the cam 25 is set for a given web width as indicated on the scale 53 by turning the hand wheel or lever 49. The hydraulic system is adjusted so that the downward pressure upon the pistons 94 is sufficient to bear a portion of the weight of the core assembly 13, the weight of the cables 18 and 7 which are taut, to overcome the friction of moving parts and to allow a portion of the weight of the core assembly 13 to bear upon the drums 11 and 12 to apply the desired pressure and tension upon the web 16 which will be wound up into the roll 17.

As the web 16 is wound and the roll 17 grows in size, the winder shaft 13' supported in the slideable bearings 14 rises and causes the cables 18 and 7 to rotate the sheaves 20. The sheaves 20 being fixed to the shaft 21 will turn the shaft 21, the sleeve 81 fixed thereto and the compensating cam 25 keyed to the sleeve. As the cam 25 is rotated, the cam follower 26 rises. The motion of the cam follower 26 is translated to the hydraulic system by the action of the lever end 29' upon the pin 34 of the calibrated adjustable relief valve 35. This results in a corresponding increase in pressure being translated downwardly upon the pistons 94 to compensate for the increases in pressure of the roll 17 upon the drums 11 and 12. The effect is to maintain the pressure and tension constant on the web 16 between the roll 17 and the rotating drums 11 and 12.

Referring to the hydraulic system diagrammatically illustrated in Figures 4 and 4-A, the handle 39' of the selector valve 39 is initially placed in position B and the handle 41 of the three-way valve 40 is initially placed in position D which is the position for automatic control. As the drums 11 and 12 are rotated and the web 16 is being wound on the core assembly 13, the pin 34

is gradually depressed by the mechanism heretofore described. The gradual downward movement of the pin 34 causes a commensurate increase in pressure in the line 104 and the line 105 through the selector valve 39. The effect upon the balanced piston valve 38 is to cause the pressure to be likewise increased in the lines 107, 108 and 111 thereby causing the pistons 94 to be moved downwardly an amount proportional to the pressure transmitted to the oil in the system by the movement of the pin 34. With the handle 41 of the three-way valve 40 in position D for automatic control, the lines 107 and 108 are directly connected. Thus, the pressure exerted upon the pistons 94 is at all times directly responsive to the movement of the pin 34. The movement of the pin 34 is directly responsive to the rotation of the cam 25 which in turn is directly responsive to the movement of the cables 7 and 19 which turn the shaft 21 as the web is being wound. Hence as the weight of the roll 17 increases, the roll 17 is commensurately lifted by the cables 7 and 19 to thereby maintain the desired and initially set pressure between the core assembly 13 and the rotating drums 11 and 12.

After the formation of a fully wound roll 17, the rotation of the drums 11 and 12 is stopped and the hand lever 41 of the three-way valve 40 is moved to position E which is the neutral or stop position. The hand lever 39' of the selector valve 39 is turned towards position C thereby blocking the oil from line 104 and causing the pump 37 to supply a maximum of pressure to the piston of the piston valve 38. When this takes place, the valve 38 opens fully and allows the maximum pressure to be applied downwardly upon the pistons 94. Thus, by gradually turning the lever handle 39' from position B to position C, the fully wound roll 17 having the radius R upon the core assembly 13 may be manually lifted from the guides 15. To lower the assembly to a suitable storage space, the hand lever 41 of the three-way valve 40 is gradually moved toward position F thereby causing the pressure exerted by the pump 37 to be directed through valve 40 and the lines 109 and 110 to cause the pressure to be exerted on the bottom faces of the pistons 94. This results in the pistons 94 being moved upwardly and the gradual lowering of the assembly held by the cables 7 and 19, the cables unwinding from the sheaves 20. After the assembly of core and wound web material is deposited where desired, the split bearings 14 are opened by turning the cam 6. The apparatus is then readied for another winding operation.

To wind a web of a different width, the cam 25 is moved along the shaft 21 to the desired position as indicated on the scale 53. In this manner another segment of the cam is presented to the cam follower 26 which will give a corresponding compensating pressure to the pistons 94 in the hydraulic system for a roll of the width being wound.

To assure that the component of contact pressure between the roll 17 and the drums 11 and 12 remains constant for webs of different width, notwithstanding that the core assembly 13 is the same, the cam 25 is cut or formed to compensate or reflect such component of contact pressure when the cam follower 26 is in contact with its surface. Thus the pressure upon the web is at all times constant regardless of the linear width of contact between the roll being wound and the drums 11 and 12.

The effective length of the bar 27 of the linkage described is adjustable and permits changing the cylinders 23 to any desired degree. In this manner the initial pressure between the drums 11 and 12 and the roll 17 may be suitably adjusted.

While the apparatus has been specifically described as capable of accommodating webs of different width, it is obvious that the same apparatus is suitable for compensating for weight increases for webs of different density. It is simply necessary to also calibrate the scale on member 53 in terms of density as well as width.

While the specific embodiment described includes two driven drums to frictionally engage the web being wound onto the core assembly or winder shaft, it is understood that the invention may be practiced with a single drum. Furthermore, the described apparatus may be used to wind any continuous flexible web or aligned strand material, such as paper, textiles, regenerated cellulose, metal foil, synthetic rubber or synthetic resin films, coated sheets, laminates, etc.

The present invention may be embodied in other specific forms without departing from the essential attributes thereof. It is desired that the present specific embodiment be considered in all respects as illustrative and not restrictive, reference being had to the appended claims rather than to the foregoing description to indicate the scope of the invention.

We claim:

1. A winding machine comprising a pair of driven drums, a winder shaft upon which a web is wound located at the nip of said drums, said web being wound into a roll by frictional engagement with said drums, spaced guideways, said winder shaft being journaled for movement in said guideways, a hydraulic system including a pair of cylinders each having a piston, connecting means between said winder shaft and said pistons, a cam shaft, a cam mounted on said cam shaft for rotation therewith, said connecting means rotating said cam shaft as the web is being wound, a cam follower engaging said cam, said cam follower being connected to a valve in said hydraulic system whereby movement of the wound roll away from said drums causes the hydraulic system to supply compensating pressure upon said pistons.

2. A winding machine comprising a pair of driven drums, a winder shaft upon which a web is wound located at the nip of said drums, said

web being wound into a roll by frictional engagement with said drums, spaced guideways, slideable, split bearings mounted in said guideways journaling said winder shaft for movement in said guideways, a hydraulic system including a pair of cylinders each having a piston, cables connecting the ends of said winder shaft and said pistons, a cam shaft, a cam mounted on said cam shaft for rotation therewith, said cables rotating said cam shaft as the web is being wound, a cam follower engaging said cam, said cam follower being connected to a valve in said hydraulic system whereby movement of the wound roll away from said drums causes the hydraulic system to supply compensating pressure upon said pistons.

3. A winding machine comprising a pair of driven drums, a winder shaft upon which a web is wound located at the nip of said drums, said web being wound into a roll by frictional engagement with said drums, spaced guideways, slideable, split bearings mounted in said guideways journaling said winder shaft for movement in said guideways, a hydraulic system including a pair of cylinders each having a piston, a cam shaft, spaced sheaves mounted on said cam shaft for rotation therewith, a cam mounted on said cam shaft for rotation therewith, cables connecting the ends of said winder shaft and said pistons to said sheaves, said cables causing said sheaves to rotate as the web is being wound, a cam follower engaging said cam, said cam follower being connected to a valve in said hydraulic system whereby movement of the wound roll away from said drums cause the hydraulic system to supply compensating pressure upon said pistons.
